The ornamental design for a female electric vehicle charging connector, as shown and described.

DESCRIPTION

FIG. 1 is a front perspective view of a female electric vehicle charging connector, showing the new design;
 FIG. 2 is a front perspective view thereof;
 FIG. 3 is a side perspective view thereof;
 FIG. 4 is a rear perspective view thereof;
 FIG. 5 is an opposite side perspective view thereof; and,
 FIG. 6 is a side view thereof.
